UNITED STATES PATENT OFFICE.

JOHN W. ESKHOLME, OF GLEN RIDGE, NEW JERSEY, ASSIGNOR TO RED STAR APPLIANCES, INC., OF NEW YORK, N. Y., A CORPORATION OF DELAWARE.

ENVELOPE-SEALING MACHINE.

Application filed March 9, 1925. Serial No. 14,045.

The present invention relates to machines for handling envelopes, cards, and other flat objects, and is capable of a variety of uses.

It is an object of the present invention to conveniently provide for the sealing of envelopes.

It is a further object of the invention to provide for printing with ink on a sealed envelope or on a flat card, as for instance to cancel the stamp on an envelope and to print adjacent to the cancelled stamp the name of the post office, a date, the hour and the permit number of the user.

It is a further object of the invention to count the number of envelopes, cards, or other flat objects passed through the machine, not for the benefit of the Government in calculating the amount of postage paid thereon, but for the information of the user of the machine.

Although the machine is capable of a wide variety of uses, its greatest utility lies in sealing stamped envelopes and then cancelling the Government stamp and counting the number of stamps so cancelled. Envelopes to be used in this way may be of the character now furnished by the United States Government and having the postage stamp formed directly in the paper of the envelope, or equally well, may be a plain envelope to which an adhesive Government stamp has been affixed.

When the sealed envelopes come from the machine with the stamps cancelled, and with the name of the post office and the date printed thereon, they can be delivered in bulk to the post office and there can be distributed directly into the outgoing pouches without the delays and labor incident to first placing them face up on the sorting table and then passing them through the stamp cancelling devices now commonly used by the Government employees. In other words, much of the labor now required at the post office is done before the mail reaches the post office with a consequent saving in time in placing the mail in transit to its destination.

The machine of the present invention has a new type of receiving platform on which the envelopes may be stacked horizontally with their open flaps hanging downward over the side of the platform in shingled relation, means being provided at the side of the stack for keeping the envelopes in proper alignment with a feed roll to which

they are to be delivered one by one from the bottom of the stack. The platform also includes an adjustable anti-friction device of novel character adapted by spring pressure to automatically tilt the stack as the number of envelopes in the stack progressively decreases.

The machine also embodies a novel barrier of cylindrical form coacting with the feeding roll and having a slight automatic movement in a direction opposite to that of the feeding roll whereby the wear on the barrier is distributed over its entire cylindrical face.

A moistening device and water fountain of novel construction serves to moisten the downwardly hanging flaps of the envelopes during their passage one by one over the feed roll. Transfer rolls and a coacting inclined guide serve to fold the gummed flap of an envelope upward against the body thereof. The envelope then passes to a pair of sealing rolls where it is firmly squeezed to secure good adhesion of the gummed flap.

When the envelope passes from the sealing rolls, it trips a printing mechanism which by its rolling movement over the travelling envelope cancels the postage stamp thereof and prints adjacent to the cancelling imprint other vital data, such as the name of the post office, the date, and hour of cancellation. Counting mechanism operatively connected with the printing device records the number of printed imprints and consequently, the number of stamps cancelled. The printing mechanism itself is so mounted that it can be swung upward into inverted position to give access to the dies and type with which it is equipped, and the type and dies are so secured in place that their replacement is a matter of but a moment's work, no special tools being required.

Manually controlled levers are provided for throwing the counting mechanism out of action, for throwing the printing roll out of action, and for throwing the inking roll out of action, when occasion may require, so that if desired, the machine may be operated simply as an envelope sealing machine.

Power for the machine is supplied by an electric motor compactly mounted, and those rotating elements of the machine which travel at high speed are equipped with wooden bearing sleeves which are silent in operation, and to which no lubricating oil need be applied by the operator. There is,

therefore no chance that dripping oil will mar or soil envelopes or other articles being passed through the machine.

Other details and objects of the complete machine will become clear from the following detailed description taken in conjunction with the accompanying drawings.

Fig. 1 is a side elevation of the complete machine;

45 Fig. 16 is a horizontal section on the line 16—16 of Figs. 6 and 11;

Fig. 17 is a side elevation of the transfer and sealing rolls and of associated means, whereby the flap of the envelope is closed and pressed against the body of the envelope;

50 Fig. 18 is a plan view of the same;

Fig. 19 is a transverse section on the line 19—19 of Fig. 18;

55 Fig. 20 is an end elevation of the machine as it appears when viewed from the left of Fig. 1, certain parts being omitted for greater clarity.

Frame work and receiving platform (Figs. 1, 2, 3, 4, 6, 13 and 20).

60 The frame work of the machine comprises a cast metal base 1 to which is secured, by a plurality of bolts 2, a sub-base 3 integral with which is a vertical supporting plate 4 carrying a hub 5 to serve as a bearing sup-

port for certain of the rotating elements. Secured to the vertical plate 4 by bolts 6 is a central sheet metal plate 7 on the flanged upper edge of which is bolted a sheet metal platform 8 which extends the entire length 70 of the machine. To its down-turned rear edge (Fig. 6) is bolted a long lower apron 9 which extends throughout the length of the machine. On the front down-turned edge of platform 8 is a short lower apron 10 75 (Figs. 3 and 1) to which is hinged a vertical guide plate 11 (Figs. 1 and 3). At the hinged connection is a coiled spring 12 for controlling the position of guide plate 11.

Above platform 8 and supported by a rear wall 13 bolted thereto is a cover plate 14 which covers the left hand two-thirds of the machine as viewed in Fig. 1, and which serves as the support for certain adjusting mechanisms. The front edge of cover plate 14 is carried by a front wall plate 15 (Fig. 13) secured along its lower edge by bolts 16 to a short front apron 17 bolted to the down-turned front edge of platform 8.

The receiving platform for the envelopes to be sealed and then cancelled is at the right hand end of the machine as viewed in Fig. 1, and includes a pair of anti-friction rollers 18, the details of which are shown in Figs. 2, 3 and 4.

Fig. 19 shows the moistening device from the rear and in elevation, and particularly the means for ratcheting the brush to produce an intermittent rotary movement;

Fig. 20 is a detail of a clutch as it appears in section on the line 14—14 of Fig. 12;

Fig. 21 is a plan view of the adjustable plates shown at the top of Figs. 6 and 11;

Fig. 22 is a horizontal section on the line 16—16 of Figs. 6 and 11;

Fig. 23 is a side elevation of the transfer and sealing rolls and of associated means, whereby the flap of the envelope is closed and pressed against the body of the envelope;

Fig. 24 is a plan view of the same;

Fig. 25 is a transverse section on the line 19—19 of Fig. 18;

Fig. 26 is an end elevation of the machine as it appears when viewed from the left of Fig. 1, certain parts being omitted for greater clarity.

different sizes and the bolts which connect the transverse bars 27 with the horizontal upper legs of brackets 26 are not screwed up so tight but that the operator can move the mechanism along slots 19 as the occasion may require.

If no anti-friction rollers were used and the stacked envelopes were permitted to lie flat on table 8, the frictional engagement of the lowermost envelope with the table top would be greater than is desired. It is the primary function of rollers 18 to reduce friction at this point. There is, however, much convenience and some operative advantages in having the rollers so supported by a spring that they will be depressed when a full stack of envelopes is placed over them. Except for this, there would be danger that one or more of the top envelopes might slide down between the stack and baffle plate 45 and there impede free passage of some of the envelopes over the drum 30. As soon as the operator completes the work of stacking the envelopes on the platform, rollers 18 move upward to produce a tilting of the stack, thus placing the envelopes in such an inclined position as will facilitate entrance over drum 30.

When the envelopes are stacked for insertion into the machine, the flaps are adjusted at right angles to the bodies, as indicated in Figs. 1 and 3. The lowermost envelope is brought into proper alignment with the rolls when the envelopes are placed on the receiving platform, and spring-pressed vertical plate 11 is relied on to force the stack over progressively so that the lowermost envelope will, at all times, be in proper alignment.

40 *The feeding rolls (Figs. 1, 2, 6 to 11, 15 and 16).*

The lowermost envelope from the stack is gripped between the large feeding roll or drum 30 and a small upper roll 31. Feeding roll 30 has a pair of annular recesses in its working face in each of which is secured a rubber tread 32 with corrugated or knurled faces as shown in Fig. 7. This drum 30 is mounted on a drive shaft 33 to which it is locked by a set screw 34 (Fig. 6). Shaft 33 passes through hub 5 in which is an anti-friction wood lining 35 so constituted as not to require application of lubricating oil.

55 Roll 31 has a smooth yielding face of rubber or like material and does not rotate from frictional engagement with an envelope passed between it and drum 30, but, on the contrary acts as a restraining baffle for all but the lowermost envelope and at the same time presents a yielding surface along which the envelope can be dragged by the rubber surfaces of drum 30. Platform 8 is provided with a pair of longitudinal slots 37 and 38 (Fig. 2) through which the rubber treads of

drum 30 project slightly. Roll 31 is positioned midway between these two slots, as appears from Fig. 6, and thus contacts with that part of the envelope which bridges a gap between the rubber treads 32.

70 The smooth yielding rubber face of roll 31 is subject to considerable wearing action from envelopes sliding under the roll and provision has been made for turning roll 31 with an intermittent movement to equalize the wear on its face, as hereinafter described. Roll 31 is so mounted as to be capable of various other adjustments.

Cover plate 14, at its right hand end, is pierced by three bolts 39, 40 and 41. (Fig. 15). Bolt 39 passes through a longitudinal slot in the horizontal leg of a bracket 42. The other or outer leg of this bracket is turned upwardly. Similarly, bolts 40 and 41 pass through longitudinal slots in the horizontal leg of a wide bracket 43; the other or outer leg of which is turned upwardly. Secured to these outwardly turned legs of the two brackets by bolts 44 is a baffle plate 45 (Figs. 6 and 11), one function of which is to keep the stack of envelopes from crowding forward against roll 31. Lying against the rear face of baffle plate 45 and guided along its edges by the adjacent up-turned edges of brackets 42 and 43 is a vertically movable plate 46, the upper end of which is bent over as shown in Fig. 11 to engage with a keeper 47 on the lower end of a threaded shaft 48 which passes with threaded engagement through an ear integral with baffle plate 45, and is provided at its upper end with a knob 49. (Fig. 6.) By turning this knob, plate 46 can be made to slide in its guideway. Near the lower end of the plate 46 are two integral ears 50 which are bent forward to serve as supports for a shaft 51 (Figs. 11 and 16). Shaft 51 serves as a pivot for a pair of side plates 52 joined together by an integral bar 53 and provided at their lower extremities with a shaft 54 on which roll 31 may turn. Wrapped around shaft 51 is a coiled wire spring 55, one end of which rests against plate 46, and the other end of which engages one of the side plates 52. This spring holds the roll to its work with a yielding pressure but will permit upward swinging movement of the roll above shaft 51 to accommodate envelopes differing slightly in thickness. This spring connection will take care of any change from a one-page letter to a two-page letter. When the envelopes are much thicker, as when containing circulars or pamphlets, manual adjustment can be made at knob 49 before commencing to pass the envelopes through the machine.

110 The mechanism whereby roll 31 is caused to turn with an intermittent movement to equalize the wear on its face includes a gag roller 56 preferably of soft rubber and floating between roll 31 and its 115 120 125 130

cross-bar 53. The upward thrust on roll 31 produced by its frictional contact with the passing envelope is sufficient to compress slightly the rubber of gag roll 56 and the contacting rubber face of roll 31, so that when the envelope has passed through there will be a slight rebound of these rubber elements to an extent sufficient to turn roll 31 slightly in a direction opposite to that of the traveling envelope. Therefore, in a sense roll 31 may be regarded as a spring-pressed barrier, the wearing surface of which is periodically renewed. Roll 31 can, of course, be turned by hand in a counterclockwise direction as viewed in Fig. 11 to present a new wearing surface for contact with passing envelopes. Ordinarily, however, the intermittent slow rotative movement above described will be entirely sufficient to equalize the wear. Cross-bar 53, by its bearing against the lower end of plate 46, acts as a stop to limit downward swing of roll 31.

The moistening device and its fountain (Figs. 1, 3 to 6, 8, 9 and 10).

At the right hand end of base 1, as seen in Fig. 1, are ears 57 and 58 for carrying rubber cushions 59, and tapped into those ears are bolts 60 and 61 under which is clamped a cross bar 62. Resting loosely on an upwardly bent portion of this bar is the foot 63 of an automatic water fountain. This fountain comprises a metal cup 64 with an air intake and overflow vent 65, this cup being threaded to one end of a horizontal feed pipe 66. The mouth of the cup is lined with a soft rubber collar 67 within which is loosely but closely fitted the neck of an inverted glass water bottle 68. The mouth of the bottle is at a level just below the air intake 65. This fountain is of the constant level type for water can flow out of the glass receptacle only in proportion as air flows in and air is admitted or excluded in accordance with the level of the water in the lower part of the cup, as will be well understood by those skilled in the art.

A soft rubber check valve 69 is inserted through the neck of the bottle into the position shown in Fig. 5. While the fountain is in use, this check valve rests on a leg 70 integral with the fountain cup and its leg 63, but when the water bottle is to be removed, the valve is released and seats against the neck of the bottle to prevent spilling any residue of water while lifting the bottle out for refilling.

To refill the bottle after removing it from the fountain the operator withdraws the soft rubber check valve 69, as if it were a cork, thus leaving the neck of the bottle unobstructed for filling. The valve is then pushed back into the bottle, and it makes no difference which end is inserted for both ends are alike. The cross section of the

stem is such as to allow ample space for the passage of air upward and the passage of water downward.

The moistening device, together with the fountain, are easily removable from the machine for purposes of adjustment, cleaning, etc. To insure ease of removal, these elements are fastened to sub-base 3 by a single bolt 71 which passes through a lug 72 integral with the casting 73 which serves as a well for the moistening water and as a support for various other elements. Feed pipe 66 is threaded into a casting 73. Along the bottom edge of casting 73 are two lugs 74 and 75 bevelled to engage with the inclined front edge of a pair of lugs 76 integral with sub-base 3 (Fig. 3). The tightening of bolt 71 brings these inclined faces into wedging engagement and insures accurate alignment of all of the parts associated with casting 73.

A sheet metal box 77 with a detachable cover 78 encloses the moving elements of the moistening device.

The moving elements of the moistening device include an intermittently rotating sheet metal drum 79 within the flanged periphery of which is secured an annular brush 80 with outwardly projecting bristles. This drum turns slowly with an intermittent movement to moisten the bristles by progressive submergence of them in the water of the well 73, but with opportunity for the bristles to drain before being brought into contact with the gummed flaps of envelopes to be sealed.

Drum 79 is secured by a nut 81 to a threaded bushing 82, which is mounted on a bolt 83 on which it can freely turn. Bolted to drum 79 is a sheet metal drum 84 with a flange at its outer edge against which bears a frictional ratcheting device now to be described.

The frictional ratcheting device whereby the moistening brush is given an intermittent rotary movement comprises a dog 85 (Fig. 10) pivoted at 86 to the upper end of an oscillating arm 87. That arm is mounted on bushing 82 (Fig. 8) and is free to swing thereon. Integral with dog 85 is a weight 88, the lower edge of which is kerfed to form a tongue 89 which is bent at right angles to the weight so that it can strike against the edge of bar 87 and thus serve to keep the dog in convenient position for reassembly in case the mechanism is taken apart for cleaning. At 86 (Fig. 6) is a stub shaft on which dog 85 can swing, this shaft being threaded through arm 87 and secured by a nut 90. Beyond the threaded portion of the stub shaft is a cylindrical portion 91 (Figs. 6 and 9) which serves as a pin for engagement with a slot 92 in the upper end of a pivotally mounted oscillating lever 93. This lever 93 is free

- to swing about a stub shaft 94 supported by box 77 and equipped with a collar, a nut, and a lock nut as shown in Fig. 6. The oscillating movement is imparted to lever 93 by means of a cam 95 which is straddled by the bifurcated lower end of lever 93. This cam is eccentrically mounted and is free to rotate on the reduced cylindrical end 96 of bolt 83. A bushing 97 is threaded to 10 that bolt and is externally threaded to receive a nut 98, the function of which is to grip the wall of box 77 and hold bolt 83 and its associated parts in proper working relation.
- 15 A simple form of clutch serves to establish driving connection between the main driving shaft 33 (Fig. 6) and the eccentric cam 95. This clutch consists of a pin 99 projecting at the end of the hub of the drum 30 and adapted by rotary movement to strike against a similar pin 100 projecting from the side face of cam 95. A gag roller 79 holds drum 79 against rotation in reverse direction.
- 20 25 The front wall of box 77 extends slightly about the axis of bolt 83 but is provided with an upwardly extending ear 101 through which passes a bolt 102 to secure the box to the front apron 15 and give support thereto.
- 30 When an envelope is passed over drum 30 its depending gummed flap wipes across the damp bristles of the annular brush 80 and the envelope then is pulled forward by the 35 transfer rolls and ultimately is sealed at the next pair of rolls. The bristles of the brush are kept in a properly moistened condition by periodic submergence in the water of the well 73 and the intermittent rotary 40 movement of the brush is slow enough to protect against too much moisture in the bristles across which the envelope is wiped.
- 45 When the machine is started up in the morning after it has been standing over night the bristles at the top of the drum will have dried out to such an extent as to be ineffective. There are, however, finger holes in the drum 79 accessible from the front of the machine so that the operator 50 can turn the drum by hand to bring properly moistened bristles into active position preparatory to starting the machine. Except for this the first few envelopes passed through the machine might not have their 55 flaps sufficiently moistened.
- The transfer and sealing mechanisms (Figs. 1, 2, 12, 13, 14, 17, 18 and 19).*
- 60 The transfer mechanism is used to forward the envelope from the moistening device to the sealing rollers and, as shown in Fig. 12, comprises an upper roller carried on a shaft 103 and consisting of annular castings 104 and 105 bolted together within 65 a metal tube 106. Each casting is lined with an oil-less wood sleeve so that its bearing on shaft 103 is suited to high speed without the need for applying lubricating oil. Tube 106 has a rubber face 107. This upper roll is spring supported as herein-after described.
- 70 The other roller of the transfer mechanism comprises a rubber cylinder 108 carried on a pair of castings 109 and 110 secured together as shown in Fig. 12 by two 75 bolts 111 and 112, each of which cooperates with a threaded sleeve and a companion bolt. This lower roller is lined by two abutting oil-less wooden sleeves 113 which are free to turn on shaft 114.
- 80 Shaft 114 is bolted at one end to apron 9. The other end is rigidly secured by a bolt to the downwardly extending ear 115 of a bracket, the upper or horizontal position of which is fastened by four screws 116 (Fig. 2) against the lower face of platform 8. This bracket has another and shorter depending ear 117 to support the outer end 85 of a stationary shaft 118 on which is a wood bearing sleeve 119, and a rubber auxiliary 90 roller 120 which acts as complementary to the main lower roll and is driven by frictional engagement with the envelopes. The lower roller cannot well be made of the same width as the upper roller because of the 95 presence of an inclined sheet metal guide 121 used to fold inwardly the moistened flaps of the envelopes. This inclined guide 121 is a prolongation of the front sheet metal wall 15 and acts progressively on the envelope flaps to swing them inward against the body of the envelope. The transfer rollers serve to hold the envelope against the 100 guide while at the same time advancing the envelope to and into the sealing rollers.
- 105 The upper sealing roll 122 (Fig. 13) is constructed essentially like the upper transfer roll.
- 110 The lower sealing roller 123 is constructed essentially like the lower transfer roller excepting that it is of greater width. It is mounted on a stationary bar 124 bolted at one end to apron 9 and at the other end to 115 apron 17.
- 120 Before the envelope reaches this pair of sealing rollers the gummed flap will have been folded into position against the body of the envelope so that the envelope 125 (Fig. 13) can be squeezed between the rubber faces of the rollers to complete the sealing.
- 125 The upper transfer roller and the upper sealing roller are yieldingly mounted in a manner now to be described. The upper transfer roller has its shaft 103 rigidly bolted to the free ends of a pair of plates 126 (Fig. 18) which are connected by an integral cross piece 127 and are pivoted on a stationary bar 128 bolted between rear wall 13 and front wall 15. The upper sealing 130

roller 122 has its shaft 129 similarly mounted on the free ends of plates 130 which are connected by a cross piece 131 and are pivoted on shaft 128. Positioned above cross bars 127 and 131 is a sheet metal spring 132 having four downwardly extending fingers 133 (Fig. 19) two of which press downward on cross pieces 127, and two of which press downward on cross piece 131. This 5 spring is held to its work by an adjusting bolt 134, the lower end of which is anchored in a U-shaped fitting threaded on bar 128. Integral with cross piece 127 are a pair of lugs 136 turned up from the cross piece itself and serving to keep the fingers of the spring from swinging around on bolt 134. The companion cross piece 131 is similarly equipped.

From the sealing rollers the envelope is 20 advanced to the printing mechanism.

The drive (Figs. 1, 2, 6, 12, 13 and 14).

The machine as a whole is driven by an electric motor 282 (Fig. 1) with its base 283 bolted to a transverse cross bar 284 bolted to base 1, as shown. The drive is through a round belt 285 to speed-reducing pulleys 286 and 287. The latter is connected by a belt 289 to a pulley 288 (Fig. 6). Pulley 288 is secured to drive shaft 33 by a set screw 290. Integral with pulley 288 is a larger pulley 291 having a belt 292 passing to a pulley 293 (Fig. 12) which is formed integral with a cylindrical sleeve 294 carried at either end on anti-friction wooden bearing sleeves 295 and 296.

The end of sleeve 294 most remote from pulley 293 is cut to form a ratchet wheel 297 (Fig. 14). Pawls 298 and 299 pivoted 40 on bolts 111 and 112 engage the teeth of this ratchet, and are biased toward the ratchet by wire springs 300 and 301 each of which is wrapped around an anchoring screw 302 and has a free end bearing against one of the pawls, as shown in Fig. 14. It is through this ratchet that a driving connection is established between sleeve 294 and the lower transfer rollers of Fig. 12.

The normal peripheral speed of the lower 50 transfer roll is slightly faster than the peripheral speed of the large feeding drum 30.

A driving connection to the next pair of rolls is effected by means of a pulley 303 (Fig. 12) integral with pulley 293 and connected by a belt 304 to a pulley 305 (Fig. 13) on a sleeve 306 equipped with anti-friction sleeves 307 and 308 of wood, as shown in Fig. 13. The diameter of pulley 305 is slightly less than that of pulley 303, and, 55 consequently, the peripheral speed of the sealing rolls 122 and 123 is slightly greater than the peripheral speed of the transfer rolls through which the envelope passes to reach the sealing rolls. The sealing rolls 60 thus have a slight tendency to snatch the

envelope out of the transfer rolls, thereby 70 guarding against any buckling in the envelope during its transit from one pair of rolls to the other. But the envelope cannot be subjected to a pull severe enough to endanger it for under such a pull the pawls of Fig. 14 will lift their respective springs and permit the transfer rolls to rotate faster than the sleeve with which they are normally connected through the ratchet wheel. 75 Consequently, the tension on the envelope is limited by the pressure with which springs 300 and 301 hold their respective dogs against the ratchet teeth. This is negligible.

Driving connection from sleeve 306 to the 80 lower sealing roll 123 is established through a ratchet drive of the same kind heretofore described in connection with Fig. 14.

Sleeve 306 is provided with a pulley 309 and a belt 310 by which power is delivered 85 to pulley 311 (Fig. 2) on shaft 139, which is the shaft of the lower printing roll 137. Pulley 311 is slightly smaller than pulley 309 so that the printing rolls tend slightly to pull the envelopes from the sealing rolls, 90 the ultimate tension on the envelope being safe-guarded by the ratchet connection between sleeve 306 and the lower sealing roll 123.

If the envelope which has engaged with 95 the printing rolls is of such length as simultaneously to be engaged both by the sealing rolls and by the transfer rolls, the speed at which the envelope travels is controlled by the peripheral speed of the printing rolls, 100 the other two pairs overrunning their ratchets sufficiently to protect the envelope from undue strain. Inasmuch as all of the upper rolls are driven by frictional engagement, the envelope is protected from such rubbing as might smear a type-written address thereon.

To operate the machine, the addressed and filled envelopes are placed horizontally in a 105 stack on the receiving platform, with their gummed flaps hanging down in shingled relation to one another and their stamped ends toward drum 30. The lowermost envelope of the stack is caught between the feed rollers and pulled out from beneath the stack and advanced across the laterally projecting moist bristles of the moistening brush. The upper retarding or separating roller meantime acts as a guard or barrier to prevent advancement of other envelopes of the stack. The moistened envelope passes directly forward through the transfer rolls while its downwardly hanging flap strikes against an inclined plate and is gradually folded upward against the horizontal body of the envelope, so that when the envelope reaches the sealing rolls, the flap can be squeezed tightly against the envelope. The sealed envelope then passes to the printing 115 rolls where the postage stamp is cancelled 120 125 130

and the name of the post office and the date and hour and the user's permit number are printed adjacent to the cancelled stamp as described in my copending application, Serial No. 96,593, filed November 17, 1925.

A great variety of changes may be made in details of the structure and in the mode of operation of the several parts without departing from the spirit of the invention as defined by the appended claims. In a divisional application, Serial No. 69,592, filed November 17th, 1925, claims are presented on novel features of the feeding mechanism and associated mechanism above described, and in a divisional application, Serial No. 69,593, filed November 17, 1925, claims are presented on the printing mechanism, the counting mechanism, and adjuncts and associated elements above described.

20 I claim:

1. In a machine of the character described, the combination of a moistening device having a well for liquid and a fountain of the constant level type for replenishing the liquid in such well, said fountain having a cup with an air inlet and a separate water outlet, and an inverted water bottle with its mouth below the level of said air inlet, said bottle being removable for replenishing and having a reversible soft rubber check valve therein, substantially as described.

2. In a machine of the character described, the combination of a cup having an air intake, a rubber collar within said cup, an inverted water bottle supported in said collar with its mouth slightly below said air inlet to insure substantially constant level of water in said cup, and a check valve in said bottle to prevent spilling the residue of liquid when this bottle is lifted out for refilling, said check valve being easily removable through the neck of said bottle.

3. In a machine of the character described, the combination of a cup having an air intake, a rubber collar within said cup, an inverted water bottle supported in said collar with its mouth slightly below said air inlet to insure substantially constant level of water in said cup, and a removable check valve in said bottle to prevent spilling the residue of liquid when this bottle is lifted out for refilling, said check valve having symmetrically formed ends so that it will function properly whichever end is inserted in the bottle.

4. In a machine of the character described, the combination of a cup having an air intake, a rubber collar within said cup, an inverted water bottle supported in said collar with its mouth slightly below said air inlet to insure substantially constant level of water in said cup, and a check valve in said bottle to prevent spilling the residue of liquid when this bottle is lifted out for

refilling, said check valve being of soft rubber so that it can easily be removed to open the neck of the bottle for refilling, and being of the same shape at both ends so that it will function properly whichever end is forced into the bottle after refilling.

5. In a machine of the character described, a water fountain of the constant level type comprising a metal cup having an air intake and an overflow spout beneath the same and having a lug centrally positioned in the bottom of the cup, an inverted glass bottle seated in said cup with its mouth slightly below said air inlet and a check valve in said bottle, said check valve being made of soft rubber to permit withdrawal from the bottle and being so shaped as to operate properly whichever end is inserted into the bottle after refilling, said valve being of such a length that when said bottle is in normal position in said cup the valve will rest on the lug at the bottom of the cup to permit free entrance of air into the bottle and free exit of water from the bottle.

6. In a machine of the character described, a base member, a feeding drum secured to said base member for feeding envelopes into the machine, a rotary moistening device, and a single means for securing said moistening device to said base member in a predetermined position relative to said drum, whereby said moistening device may be readily removed for cleaning.

7. In a machine of the character described, a base member, a feeding drum secured to said base member, a rotary moistening device and means including lugs on said base member and said device, and a single bolt for securing said device to said base member with said moistening device coaxially disposed with respect to said feeding drum, whereby said moistening device may be readily removed for cleaning.

8. In a machine of the character described, the combination of a feeding drum over which envelopes may pass with their bodies horizontal and their flaps vertical, a rotary moistening brush coaxial with said drum and across the end face of which the envelope flaps are wiped to moisten the gum thereof, and means for rotating said brush to periodically immerse the bristles thereof in a liquid.

9. In a machine of the character described, the combination of a feeding drum over which envelopes may pass with their bodies horizontal and their flaps vertical, a rotary moistening brush coaxial with said drum and across the end face of which the envelope flaps are wiped to moisten the gum thereof, and means for intermittently rotating said brush to periodically immerse the bristles thereof in a liquid.

10. In a machine of the character de-

scribed, the combination of a feeding drum over which envelopes may pass with their bodies horizontal and their flaps vertical, a rotary moistening brush coaxial with said drum and across the end face of which the envelope flaps are wiped to moisten the gum thereof, a well into which the lower edge of said brush dips, and means for ratcheting said brush on its axis to periodically moisten the bristles thereof with liquid held in said well.

11. In a machine of the character described, the combination of a feeding drum over which envelopes may pass with their bodies horizontal and their flaps vertical, a rotary moistening brush coaxial with said drum and across the end face of which the envelope flaps are wiped to moisten the gum thereof, and a ratchet driving connection between said drum and said moistening brush whereby said brush is intermittently rotated to periodically moisten the bristles thereof in a liquid.

12. In a machine of the character described, the combination of a feeding drum over which envelopes may pass with their bodies horizontal and their flaps vertical and a rotary moistening device co-axial with said drum and across the end face of which the envelope flaps are wiped to moisten the gum thereof.

13. In a machine of the character described, the combination of a feeding drum, a brush co-axial therewith, a drum supporting said brush, and a well into which said brush dips, said brush-supporting drum having hand holes to facilitate manual rotation of the brush when the bristles thereof have become too dry through standing idle.

14. In a machine of the character described, the combination of a feeding drum, a brush-supporting drum coaxial therewith, ratcheting means operatively connected with said brush-supporting drum, and a detachable driving connection between said feeding drum and said ratcheting means.

15. In a device of the character described, the combination of a feeding drum, a moistening drum coaxial therewith, a gravity actuated dog frictionally engaging the inside of said moistening drum, a swinging arm operatively connected to intermittently swing said dog and thereby turn the drum with which it engages, a cam for swinging said arm and means for driving said cam from said feeding drum.

16. In a machine of the character described, a feeding drum over which an envelope may be passed, a pair of transfer rolls into which said envelope is fed, the lowermost of said rolls being of less width than the upper roll, a small auxiliary roll at the side of said lower transfer roll to assist in holding said envelope against the upper transfer roll, and an inclined metal guide beneath said transfer rolls in position to fold the depending flap of the envelope toward the body thereof during transit of the envelope through said transfer rolls.

17. In a machine of the character described, the combination of a pair of transfer rolls, a swinging frame in which the uppermost of said rolls is mounted, a shaft on which said frame may swing, and a spring operatively positioned to press downward on said frame and urge the uppermost transfer roll toward its companion roll.

18. In a machine of the character described, the combination of a pair of sealing rolls between which a moistened envelope may be passed for compression, the lowermost sealing roll being power driven and the uppermost sealing roll being driven by frictional engagement with its companion roll or with an envelope passing between a the two, a frame in which said upper roll may rotate, a shaft about which said frame may swing, a bolt operatively connected to said shaft, and a leaf spring engaging said frame and operatively connected for adjustment by said bolt to increase or decrease the pressure of said upper roll on an envelope passing between said rolls.

19. In a machine of the character described, the combination of a pair of horizontal transfer rolls, the lowermost of which is power driven, a pair of horizontal sealing rolls the lowermost of which is power driven, a frame supporting the upper transfer roll, a second frame supporting the upper sealing roll, a single shaft by which both of said frames are supported and about which they may swing, an adjusting bolt operatively connected to said shaft, and a leaf spring adapted for adjustment by said bolt and bearing against both of said frames to push both of them downward with substantially equal force.

In testimony whereof I affix my signature.

JOHN W. ESKHÖLME.
